UNITED STATES PATENT OFFICE.

JOHN F. MILLER, OF MARTIN'S FERRY, OHIO.

DESIGN FOR A LAMP-CHIMNEY.

SPECIFICATION forming part of Design No. 17,853, dated November 1, 1887.

Application filed June 23, 1887. Serial No. 212,322. Term of patent 3½ years.

To all whom it may concern:

Be it known that I, JOHN F. MILLER, of Martin's Ferry, in the county of Belmont and State of Ohio, have invented a new and original Design for Lamp Chimneys; and I do hereby declare the following to be a full, clear, and exact description thereof.

The design is shown in the accompanying drawings, in which Figure 1 is a side view of a lamp-chimney ornamented with the design, and Fig. 2 is a horizontal cross-section on the line *x x* of Fig. 1.

Like symbols of reference indicate like parts in each.

15 The leading features of the design consist in a lamp-chimney ornamented with a series of separated parallel ribbed stripes and intervening plain stripes, the ribbed stripes forming a contrast of color with the intervening 20 plain stripes. A chimney so ornamented pro-

duces a beautiful effect when illuminated by the light of the lamp.

In the drawings, *A* is the chimney. *b b* are the ribbed stripes, and *c c* are the intervening plain stripes. The stripes are quite narrow and blend together in appearance.

I claim—

The design for lamp chimneys herein shown and described, which consists in a lamp-chimney ornamented with separated parallel 30 ribbed stripes *b b* and intervening plain stripes, *c c*, said ribbed stripes forming a contrast in color with the intervening plain stripes.

In testimony whereof I have hereunto set my hand this 20th day of June, A. D. 1887.

JOHN F. MILLER.
